UNITED STATES PATENT OFFICE

2,513,695

ELECTRIC SWITCH

Hermon L. Van Valkenburg, Wauwatosa, Wis.,
assignor to Square D Company, Detroit, Mich.,
a corporation of Michigan

Application January 12, 1945, Serial No. 572,472

1 Claim. (Cl. 200—104)

1

This invention relates to an electromagnetically operated electric switch and has for one of its objects the provision of a simple and compact form of such switch.

Another object of this invention is to provide an electric switch which is operable in any position of mounting.

Another object of the invention is to provide an electric switch of the enclosed compact type with improved means for front accessibility and demounting of the contacts and operating parts of the switch.

Other objects and features of the invention will be readily apparent to those skilled in the art from the specification and appended drawing illustrating certain preferred embodiments in which:

Figure 1 is a top plan view of an electric switch according to the present invention with part of the contact enclosure broken away.

Figure 2 is a view partly in side elevation and partly in vertical section along the line II—II of Figure 1.

Figure 3 is a sectional view on the line III—III of Figure 1.

Figure 4 is a view partly in side elevation and partly in vertical section on the line IV—IV of Figure 1.

The electric switch, according to the present invention, comprises a mounting plate 1 adapted to be connected to a support by means of studs 2. Upon the plate 1 are mounted four supporting posts 3 as means of studs 4. On the upper pair of supporting posts 3 is mounted an insulating block 5 as by means of studs 6 threaded into the posts. Upon the forward ends of the lower pair of supporting posts 3 is mounted an insulating block 7 by means of studs 8 threaded into the supporting posts, the insulating blocks 5 and 7 being spaced apart to provide a transverse opening 9 therebetween. Upon the insulating block 5 are mounted a plurality of spaced conducting connectors 11 as by means of studs 12 and the lower ends of the connector 11 support stationary contacts 13. Similarly, upon the block 7 are mounted the connectors 14 by means of studs 15 and adjacent their upper ends carry stationary contacts 16 vertically aligned with the contacts 13 on the block 5. The connectors 11 and 14 are provided with terminal screws 17 for the attachment of circuit wiring.

Upon the plate 1 between the posts 3 is mounted an E-shaped magnet structure 18 having upper and lower supporting plates terminating in flanges 19 secured to the back plate 1 by studs

2

21. Upon the central core of the magnet 18 is mounted an energizing coil 22 maintained in place thereon by a pair of L-shaped brackets 23 secured to the magnet frame by the bolt 24. At 5 opposite sides of the plate 1 between the supporting posts 3 thereof are mounted a pair of guide posts 25 having reduced portions 26 on which are disposed the biasing springs 27 and upon which are slidably mounted an insulating contact carrier 28. The back surface of the carrier 28 is cut out at 29 to receive an armature 31 maintained in place for limited pivotal movement upon the pin 32. The back surfaces of the blocks 5 and 7 are cut out at 33 to receive the insulating carrier 28 and determine its forward limit of travel to which it is biased by the springs 27. From the forward face of the carrier 28 project three insulating posts 34 which pass forwardly through the opening 9 between the blocks 10 5 and 7. Secured in the posts 34 and extending 15 forwardly thereof are movable contact and spring guide supporting posts 35 upon which are slidably mounted the bridging contact plates 36 carrying the movable contacts 37. The plates 36 are 20 biased toward the posts 34 by contact pressure springs 38 whose forward ends are maintained 25 by cup washers 39 and cotter pins 41.

Forwardly of the insulating blocks 5 and 7 is 30 mounted an insulating contact enclosing block 42 having three chambers 43 therein in each of which is disposed a pair of the spaced stationary contacts 13 and 16 and a bridging contact plate 6. The front surfaces of the blocks 5 and 7 and the dividing walls of the block 42 are provided 35 with interlocking tongues and grooves indicated at 44 in Figure 1. The contact enclosing block 42 is maintained in place by means of studs 45 threaded into the forward ends of the guide posts 25.

40. The operation of the switch will be readily apparent. When the coil 22 is energized, the magnet 18 will attract the armature 31 to move the carrier 28 rectilinearly upon the guide posts 25. The contacts 37 engage the contacts 13 and 16 45 prior to seating of the armature 31 and its continued movement into engagement with the magnet stresses the springs 38 to apply pressure to the cooperating contacts. This movement of the carrier 28 is against the bias of the return springs 27. To move the switch to the off position, the coil 22 is deenergized, whereupon the springs 27 return the carrier 28 to the position shown in the drawings in which the contacts 37 are separate from the spaced stationary contacts 13 and 16 to open the circuit through the switch. 50

The switch, as shown and described, is of extremely compact form while of substantial interrupting capacity, and is particularly adapted for nesting with other similar switches to occupy a relatively small space. Further, with the use of the springs 27, the switch will operate in any position since it does not depend upon gravity to effect movement of the contacts. Although the normal operating position will be as shown in the drawings with the mounting plate 1 constituting the back plate and with the carrier 28 moving in a horizontal direction, any desired mounting position may be used.

A feature of this switch lies in the ready accessibility of parts for inspection and for demounting entirely from the front of the switch and regardless of the disposition of other switches or other structures immediately adjacent thereto. The removal of the studs 45 permits the insulating enclosure or hood 42 to be removed whereupon all of the stationary and movable contacts are exposed for inspection. Removal of the studs 6 will permit removal of the insulating block 5 and the three stationary contacts 13 mounted thereon. Similarly, removal of the studs 8 permits removal of the contact block 7 and the stationary contacts 16 supported thereon. With the blocks 5 and 7 removed, the carrier 28 may be slid forwardly and removed from the guide posts 25 without further manipulation. Removal of the studs 21 provides for the frontwise removal of the magnet 18 and the energizing coil 22 thereon. It is thus seen that all parts of the switch are readily removable in a forward direction regardless of the immediate juxtaposition of other switches or other structures.

While certain preferred embodiments of the invention have been specifically disclosed, it is understood that the invention is not limited thereto, 40

as many variations will be readily apparent to those skilled in the art.

What is claimed is:

5 In an electric switch, a mounting plate, switch operating means mounted on said mounting plate, spaced insulating plates mounted on said plate forwardly of said operating means, a carrier mounted on said plate forwardly of said operating means and having portions projecting forwardly through the space between the plates, stationary contacts on the insulating plates, movable contacts mounted on said carrier forward projecting portions and cooperating with said stationary contacts to perform the switching operations, an insulating hood mounted in front of the insulating plates and cooperating therewith to enclose the cooperating sets of contacts, said insulating hood being readily removable in a forward direction, said insulating plates and carrier being thereafter readily removable in a forward direction and said operating means being readily removable in a forward direction after removal of said insulating plates and carrier, whereby to promote the ready accessibility and assembly of the elements of the switch.
